(No Model.)

D. MILLS.

BUTTON HOLE SEWING MACHINE.

No. 313,438.

Patented Mar. 3, 1885.

UNITED STATES PATENT OFFICE.

DANIEL MILLS, OF PHILADELPHIA, PENNSYLVANIA, ASSIGNOR TO THE UNITED STATES AUTOMATIC BUTTON HOLE SEWING MACHINE COMPANY, OF SAME PLACE.

BUTTON-HOLE SEWING-MACHINE.

SPECIFICATION forming part of Letters Patent No. 313,438, dated March 3, 1885.

Application filed April 5, 1884. (No model.)

To all whom it may concern:

Be it known that I, DANIEL MILLS, a citizen of the United States, and a resident of Philadelphia, Pennsylvania, have invented 5 certain Improvements in Button-Hole Sewing-Machines, of which the following is a specification.

My invention consists of certain improvements in the construction of the button-hole 10 sewing mechanism for which I applied for Letters Patent of the United States August 6, 1883, Serial No. 102,914, the main object of my present improvements being to make the 15 attachment more compact. This object I attain as more fully described hereinafter, reference being had to the accompanying drawings, in which—

Figure 1 is a plan view of my improvement. Fig. 2 is a sectional plan on the line 1 2, Fig. 20 3. Fig. 3 is a side view looking in the direction of the arrow 1, Fig. 1; and Fig. 4 is a transverse section on the line 3 4, Fig. 1.

To facilitate the explanation and comprehension of my present improvement, I have 25 used the same letters of reference, so far as applicable, as in my application above referred to.

The base H of the attachment is provided with the usual throat-plate, h, by which it 30 may be applied to the bed-plate of a sewing-machine, and motion is imparted to the movable parts of the device from the reciprocating needle-bar of the said machine, a pin on this needle-bar being adapted to an open slot, 35 b, in an arm of the bell-crank lever D, pivoted to the upright d on the base H. This lever D occupies a position at right angles to that occupied by the similar lever in the attachment shown in my previous application referred to, and the lever F, pivoted at f to the base-plate, and vibrated by the lever D, lies transversely across the base-plate, below the vibrator G and slide G', instead of occupying a position alongside them.

45 The lever F carries at its outer end the pin or anti-friction roller l, for acting on the arm l' of the friction feed-disk N, Figs. 1, 3, and 4, which is mounted to turn on the fixed pin R on the base-plate H. I have not illustrated

the details of this friction-feed, nor will it 50 be necessary to describe them, as they may be similar to those described in my former patents and applications. Suffice it to say that the reciprocating motion of the needle-bar imparts an intermittent rotary motion to the 55 disk N through the medium of the levers D and F, the extent of this feed motion being regulated by the screw-stop r, which limits the return movement of the arm l' under the action of the pull-spring r', Fig. 1. 60

The vibrating plate G is pivoted to a pin, g, on the base, Fig. 2, as heretofore, and carries the slide G', with its cloth-clamp K, and the longitudinal feed motion is imparted to this slide from the disk N by means of its cam-groove n acting on an anti-friction roller, m, on the bent arm M, pivoted at m' to a lug on the base, and connected by the adjustable bolt m² to the arm m', which in turn is connected to the vibrator through the medium of the 70 link or pitman L. (Indicated by dotted lines in Fig. 1.) In my former attachment this pitman was a long rod forked to embrace the cam carried by the disk N; but I prefer to use the short link shown in the accompanying 75 drawings.

The devices for imparting the vibrating motion to the plate G are similar to those described in my previous application; but instead of mounting the three-cornered cam P 80 and its ratchet-wheel p on a separate pivot-post, I mount them, as shown in Figs. 2 and 4, on the same post, R, on which the disk M and its stop-cam are mounted; and intermittent rotary motion is imparted to the cam P 85 by the pawl p' (on the vibrating lever F) engaging with the teeth of the wheel p. This enables me to dispense with the extension G² on the vibrator, and to pivot the yielding spring-arms E E', Fig. 2, directly to the under 90 side of the vibrator, thus obtaining a much more compact device with a more direct action of the operative parts than in my previous attachment referred to. The inward movement of the arms E E' under the action of the 95 pull-spring e is limited by pins g' g', Fig. 2, on the slide.

The detailed construction of the stop-cam T

and the corresponding yoke and projections on the vibrator to limit the motion of the latter have not been shown, as they may be precisely the same as those described in my 5 previous application cited.

I claim as my invention—

1. The combination of the vibrator of a button-hole sewing mechanism, carrying spring-arms E E', with a rotary cam for acting on 10 said arms and a stop-cam to limit the extent of motion of the said vibrator, the two cams being mounted on the same pivot-post, substantially as set forth.

2. The combination of the vibrator and slide 15 of a button-hole sewing mechanism, the said vibrator carrying spring-arms E E', with a rotary cam for acting on said arms, a stop-cam to limit the extent of motion of the vibrator, and a disk with a cam-groove for imparting feed motion to the slide, the two cams and the feed- 20 disk all being mounted on the same pivot-post, substantially as described.

3. The combination of the vibrator and slide of a button-hole sewing mechanism and cloth-clamp carried thereby with the needle-bar of 25 a sewing-machine, bell-crank lever D, transverse lever F, pivoted to the base, and carrying a pawl and a ratchet-wheel operated thereby, to impart motion to the said vibrator and slide, substantially as set forth. 30

4. The combination of the vibrator and slide of a button-hole sewing mechanism and cloth-clamp carried thereby with a friction feed-disk, N, for imparting a longitudinal feed motion to the slide, arm l', lever F, carrying a 35 pin, l, bell-crank lever D, and needle-bar of the sewing-machine, substantially as set forth.

In testimony whereof I have signed my name to this specification in the presence of two subscribing witnesses.

DANL. MILLS.
